(No Model.)

J. V. H. DITMARS.

COMBINED EASY CHAIR AND COUCH.

No. 325,326.

Patented Sept. 1, 1885.

Fig. 1.

UNITED STATES PATENT OFFICE.

JOHN V. H. DITMARS, OF NEW YORK, N. Y.

COMBINED EASY-CHAIR AND COUCH.

SPECIFICATION forming part of Letters Patent No. 325,326, dated September 1, 1885.

Application filed July 11, 1885. (No model.)

To all whom it may concern:

Be it known that I, JOHN V. H. DITMARS, of the city, county, and State of New York, have invented a new and useful Improvement 5 in a Combined Easy-Chair and Couch; and I do hereby declare that the following is a full and exact description thereof, reference being had to the accompanying drawings, and to the letters of reference marked thereon, making 10 a part of this specification, in which—

Figure 1 is a side elevation of the frame of my improved easy-chair and folding couch before it is upholstered, and when closed to form the chair. Fig. 2 is a view of the same 15 in perspective when opened out to form a couch.

The object of my invention is to obtain in simpler form than heretofore a comfortable easy-chair, which may be readily opened out 20 to form in itself a comfortable couch or lounge. To this end the back of the chair is hinged to the rear of the body-frame, so as to admit of being swung down into a horizontal plane, and a seat-frame corresponding in dimensions to 25 the body-frame is pivoted to its front edge to fold over upon the body-frame, and to open out into the same horizontal plane therewith to serve as an extension thereof. The hinged back is formed in two sections also hinged together, and which are so arranged, as hereininafter described, as that the outer section shall, when the back is opened out, automatically 30 assume an inclined position as the inner section attains the horizontal plane, and thereby 35 serve as a head-piece for the couch.

A A represent the body-frame supported at its four corners upon suitable legs, B B B; C C, a counterpart seat-frame of same dimensions, adapted to be superimposed upon the 40 body-frame, and which is hinged thereto, at the front edge thereof, by flat hinges *a a*, which permit the seat-frame to open out, with its upper surface in the same horizontal plane as the upper surface of the body-frame, and to 45 serve as an extension thereof.

The arms D D of the chair are secured to the side bars of the seat-frame C C, and are made of a height corresponding to the length of the legs B B of the body, so that when the 50 seat-frame is opened out (see Fig. 2) the arms

will rest upon the floor and support the seat-frame, the body-frame and seat-frame being brought thereby with their upper surfaces in the same horizontal plane, as shown in Fig. 2.

The back of the chair is constructed in two 55 sections, E E and E' E', of the same width as the body and seat frame, but of unequal length. These two sections are hinged together, and the inner longer section, E E, is hinged to the back edge of the body-frame A A by flat 60 hinges *b b*, corresponding to the hinges *a a* of the seat-frame C C, so as to permit said back-frame to drop into a horizontal plane to form an extension of the body-frame, in the same manner as does the seat-frame C C. 65

Upon each side of the inner sections, E E, of the back, a leg, F, preferably made of a thin stout plate of metal, is pivoted at its upper inner end to the side bar of the section, a short distance inside of the hinged joint of said 70 bar with the outer section, E' E'. This pivoted leg F is coupled with the side of the body-frame by means of a side bar or link, G, pivoted to the body frame, or to its rear leg a short distance below the hinged joint of the 75 back therewith, and to the leg F a short distance below or outside of its pivotal connection to the back-frame.

The coupling bar or link G is so adjusted in 80 length as that when the back-frame is turned up in position to form a back-frame for the chair, the leg F will be drawn into line parallel with the side bar of the section E E; hence when the back-frame drops, or is swung down upon its hinges to the level of the body-frame 85 A A, the leg F is made to swing out into a position at right angles to the section E E of the back-frame, and reaching the floor will serve as a support therefor.

A second coupling bar or link, H, is pivoted 90 to an arm, K, projecting from the outer side of the swinging leg F, and is made to engage the outer sections, E' E', of the back, by means of a lateral pin, *i*, projecting from the side bar of said section through a slot in the end of the 95 link H; hence, when the leg F swings out as the back drops, this coupling-bar will move over the pin *i* to the length of its slot, whereupon the further movement of the back, as it approaches a horizontal position, will operate 100

to turn up the outer section, E'E', into an inclined position, and when the leg F touches the floor the bar H will serve as a brace to support this outer or head section in its inclined position. When the back is swung up, the engagement of the bar H with the outer section will cause it to swing out automatically into the same plane as the inner section, E'E (see Fig. 1,) so that when the back-frame is folded up to form the back of the chair its two sections will be as one piece. The back, when swung up, is secured by means of two hooks, L L, which projecting from the legs F F are engaged by swinging links M M, pivoted upon the inner ends of the arms D D, so as to drop out and project horizontally therefrom when the arms are brought into position on the chair, (see Fig. 1,) but which will drop closely against the ends of the arms when they are thrown over upon the floor to support the seat-frame in position for the couch. (See Fig. 2.) The links M M are supported in their horizontal position when the arms are on the chair (see Fig. 1) by means of lugs r r, projecting centrally from the hinge by which the links are pivoted. As the back is swung up against the ends of the arms to complete the chair, the hooks L L, automatically pass under these links M M, and becoming engaged thereby will thus lock the back to the seat-frame.

The transverse bars of the frames A A C C and E E E' E' are preferably curved, as shown in the drawings, Fig. 2, to facilitate the upholstering of the combined chair and couch.

The complete folding frame thus constructed to serve as a chair or couch is strong, simple, and compact in all its parts, and when properly upholstered constitutes a neat comfortable chair, readily convertible into an equally neat and comfortable couch or lounge.

I claim as my invention—

1. The combination, with the body-frame supported upon four legs, of a seat-frame pivoted to the front edge of the body-frame to fold over thereon and open out therefrom, and which is

provided with arms fixed to serve as its supports when opened out, and of a back-frame constructed in two sections and hinged to the rear edge of the body-frame, to fold up at an angle thereto and to open out therefrom, said back-frame having its inner section supported upon a pivoted leg, and its outer section adjusted and stayed at an angle with the first by a slotted link connecting it with said leg, all substantially in the manner and for the purpose herein set forth. 55

2. The combination, with the body frame, and with the back-frame hinged thereto, constructed in two sections hinged together, of legs pivoted laterally to the outer end of the inner section, links coupling said legs each to the body-frame below its hinged joint with the back, and slotted links pivoted to offsets projecting from said legs and engaging each by means of its slot a pin upon the side of the outer hinged section, substantially in the manner and for the purpose herein set forth. 65

3. The combination, in a combined chair and couch with the body-frame, the legs pivoted laterally to the back-frame, which is hinged to the rear edge of the body-frame, the seat-frame hinged to the front edge of the body-frame, and the inner ends of the arms fixed upon said seat-frame, of links hinged to the inner end of said arms, to drop open by their weight when the arms are in position upon the chair, and hooks projecting from the pivoted legs to engage said links when the back-frame is elevated in its normal position to complete the chair, substantially in the manner and for the purpose herein set forth. 75

In testimony whereof I have signed my name to this specification in the presence of two subscribing witnesses.

JOHN V. H. DITMARS.
